ATTORNEY

UNITED STATES PATENT OFFICE.

WILLIAM W. HAYDEN, OF NEWARK, NEW JERSEY.

DESIGN FOR A MATCH-BOX.

SPECIFICATION forming part of Design No. 22,377, dated May 2, 1893.

Application filed March 11, 1893. Serial No. 465,644. Term of patent 3½ years

To all whom it may concern:

Be it known that I, WILLIAM W. HAYDEN, a citizen of the United States, and a resident of Newark, in the county of Essex and State of New Jersey, have invented and produced a new and original design to be printed, painted, cast, or otherwise placed on or worked into match-boxes, buckles, and other articles of manufacture, of which the following is a specification, reference being had to the accompanying drawing, forming a part thereof.

The figure is a side view of a metal match-box, showing my design.

A represents the body and B the top or cover of the box. On the body appears the representation of two masks *a b* arranged as shown.

Surrounding the masks and the margin of the body appears the representative of a ribbon *c* which terminates at the top of the body adjacent to the masks. On the cover B appears a bow-knot *d* of ribbon which is represented in extension of the ribbon on the body. 20

Having thus described my invention, what I claim as new, and desire to secure by Letters Patent, is—

The design for a match-box, substantially as shown and described. 25

WILLIAM W. HAYDEN.
